(57) **CLAIM**

We claim the ornamental design for a biosensor wristband, as shown and described.

DESCRIPTION

FIG. 1 is a top isometric view of a biosensor wristband;
FIG. 2 is a right side view of the biosensor wristband;
FIG. 3 is a left side view of the biosensor wristband;
FIG. 4 is a front view of the biosensor wristband;
FIG. 5 is a rear view of the biosensor wristband;
FIG. 6 is a top view of the biosensor wristband;
FIG. 7 is a bottom view of the biosensor wristband;
FIG. 8 is a bottom isometric view of the biosensor wristband;
FIG. 9 is an exploded top isometric view of a biosensor wristband;
FIG. 10 is an exploded right side view of the biosensor wristband;
FIG. 11 is an exploded left side view of the biosensor wristband;
FIG. 12 is an exploded front view of the biosensor wristband;
FIG. 13 is an exploded rear view of the biosensor wristband;
FIG. 14 is an exploded top view of the biosensor wristband;
FIG. 15 is an exploded bottom view of the biosensor wristband; and,
FIG. 16 is an exploded bottom isometric view of the biosensor wristband.

Exploded views are provided to supplement the fully assembled views. The associations of elements in the exploded views are indicated with brackets.
